UNITED STATES PATENT OFFICE.

SIGURD EDLING, OF BOSTON, MASSACHUSETTS.

HOISTING MECHANISM.

SPECIFICATION forming part of Letters Patent No. 772,138, dated October 11, 1904.

Application filed January 9, 1904. Serial No. 188,318. (No model.)

To all whom it may concern:

Be it known that I, SIGURD EDLING, residing at Boston, in the county of Suffolk and State of Massachusetts, have invented certain new and useful Improvements in Hoisting Mechanism; and I do hereby declare the following to be a full, clear, and exact description of the invention, such as will enable others skilled in the art to which it appertains to make and use the same.

This invention relates to hoisting mechanism; and it consists of an overhead trolley or carrier, as hereinafter fully described and claimed.

The object of the invention is to provide a trolley or carrier which is locked to the track automatically at intermediate points while the load is being raised or lowered.

In the drawings, Figure 1 is a side view of the trolley, showing the fall-block in its highest position. Fig. 2 is a cross-section taken on the line *xx* in Fig. 1. Fig. 3 is a side view similar to that shown in Fig. 1, but showing the trolley locked and the fall-block partially lowered.

A is an overhead track, and *1* is a carriage or frame provided with rollers *2*, which run on the track. A sheave *3* is journaled in the frame, and *4* is the hoisting-rope, which passes over the sheave *3*, under the sheave in the fall-block *5*, and has its other end secured to the anchor-bar *6* in the frame. A rope *7* is provided for moving the trolley to the left; but when the track is inclined so that the trolley can run to the left by gravity this rope is not required. The track *A* has stops *8* secured to it, and as many stops *8* as required are provided and are secured to it wherever the trolley is to be locked to it and at suitable intervals. At the left-hand end of the track a stop *8'* is provided, which is a modification of the stops *8* in form, as will be more fully described hereinafter. The fall-block *5* is provided with an eye or loop *9*, provided with laterally-projecting arms *9'*, which engage with guide-slots *11* in the side plates of the frame or carriage. A hook *10* is pivoted on a pin *12* in the frame and is provided with a finger *13* and two notches *14* and *15*. The hook is arranged at the top of the slots *11*.

A locking-lever *17* is pivoted on a pin *16* in the frame and consists of two side pieces arranged outside the frame and cross pieces or pins which work in slots or openings in the frame. The locking-lever is provided with a pin *18* at its lower part for engaging with the notches *14* and *15* of the hook, and it has a pin *19* at its upper part for engaging with the stops *8* and *8'*. The locking-lever *17* also has a pin *20* at its middle part, and *21* is a lever which is pivoted inside the frame upon the pin *20* and provided with a roller *22* at its free end. A spring *25*, secured to the frame *1*, holds the lever *21* in a prearranged position and prevents it from dropping. The locking-lever is provided with a pin *23* above the lever *21* for the said lever to engage with. A tumbler *24* is pivoted in the frame *1* upon a pin *24'*, and *26* is a spring which controls the position of the said tumbler, being secured at one end to the frame and at the other end to an arm *26'*, which is operatively connected with the said tumbler. One arm of the tumbler is normally arranged in the path of the stops *8*, and its other arm is then below the roller *22*, as shown in Fig. 1. The stop *8'* is similar to the stops *8*, but has a hook-shaped projection *28* at its left-hand end.

The operation of the mechanism is as follows: When the parts are in the positions shown in Fig. 1, the fall-block is supported by the hook *10*, which engages with the eye *9* and supports the load, so that the trolley can be moved along the track. When the trolley is moved to the left, as shown by the arrow in Fig. 1, the tumbler *24* strikes the end *b* of the stop *8* and turns the locking-lever *17* upward on its pivot by pressing the lever *21* upward against the pin *23*. In its normal position the locking-lever *17* locks the hook *10* by engaging with its notch *14*, so that the hook cannot be turned on its pivot by the weight of the load; but when the locking-lever is turned upward on its pivot by the action of the stop *8* and lever *21* the pin *18* is raised out of the notch *14*, so that the hook is free to turn on its pivot and permits the fall-block and the load supported by it to be lowered. The pin *19* at the upper part of the locking-lever is placed in engagement with the

notch *c* of the stop 8, and the stop 8 raises the tumbler above the roller 22, as shown in Fig. 3. When the locking-lever 17 is thus raised and the hook 10 lowered, as shown in Fig. 3, 5 the pin 18 engages the notch 15 of the hook and the hook is supported in a convenient position and so that the finger 13 extends across the upper parts of the slots 11. The spring 26 supports the tumbler 24 in its raised position, as shown in Fig. 3, and the spring 25 supports the lever 21 and its roller 22. When the parts are in the positions shown in Fig. 3 and the load is hoisted, the eye 9 of the fall-block raises the finger 13 and engages with 10 the hook 10, at the same time turning the said hook on its pivot-pin and permitting the locking-lever to descend by gravity to its original position, in which its pin 18 engages with the notch 14 and locks the hook. The 15 roller 22 still remaining below the tumbler, the trolley can be moved farther to the left without being operated by the intervening stops 8, as these stops 8 will merely oscillate the tumbler when they strike it. The tumbler is caused to reengage with the lever 21 when the trolley is moved to the right, as the upper arm of the tumbler then strikes the end *d* of the next stop 8, so that the other arm of the tumbler is pressed down below the 20 roller 22, the depression of the roller for this purpose being permitted by the spring 25. In order to obviate the necessity of running the trolley to the left past the end stop 8', the 25 said end stop 8' is provided with a hook-shaped projection 28, which engages with the pin 19 and operates the locking-lever 17.

In hoisting mechanism constructed as hereinbefore set forth the fall-block can be raised or lowered at any desired point along the 30 track and at any number of points along the track by securing stops 8 at such points.

What I claim is—

1. In hoisting mechanism, the combination, 35 with a track, and a trolley which runs on the said track; of a hook for supporting the fall-block pivoted to the said trolley, a locking-lever for the said hook also pivoted to the said trolley, a lifting-lever pivoted to the said locking-lever, a spring-controlled tumbler for 40 operating the said lifting-lever also pivoted to the said trolley, and a stop for operating the said tumbler secured to the said track.

2. In hoisting mechanism, the combination,

with a track, and a trolley which runs on the 55 said track and which has guide-slots at its lower part; of a fall-block provided with an eye and arms for engaging with the said slots, a sustaining-hook pivoted to the said trolley and engaging with the said eye and having a finger which projects across the said slots in 60 the path of the said eye, a locking-lever for the said hook also pivoted to the said trolley, a stop secured to the said track, a lifting-lever pivoted to the said locking-lever, and a spring-controlled tumbler for operating the 65 said lifting-lever also pivoted to the said trolley and operated by contact with the said stop.

3. In hoisting mechanism, the combination, 70 with a track, and a trolley which runs on the said track; of a hook for supporting the fall-block pivoted to the said trolley, a locking-lever for the said hook formed of two side plates pivoted outside the trolley and cross-pins between the said side plates which pass 75 through openings in the trolley-frame, a lifting-lever pivoted on one of the cross-pins of the said locking-lever, a pin on the said locking-lever for the said lifting-lever to engage with when moved upward, a spring for supporting the said lifting-lever in a prearranged position, a spring-controlled tumbler for operating the said lifting-lever also pivoted to the said trolley, and a stop for operating the 80 said tumbler secured to the said track. 85

4. In hoisting mechanism, the combination, 90 with a track, and a trolley which runs on the said track; of a hook for supporting the fall-block pivoted to the said trolley, a locking-lever for the said hook also pivoted to the 95 said trolley and provided with a pin at its upper end for locking the trolley to the said track, a lifting-lever pivoted to the said locking-lever, a spring-controlled tumbler for operating the said lifting-lever also pivoted to the said trolley, and a stop for operating the 100 said tumbler secured to the said track and provided with a notch for the said pin at the upper end of the locking-lever to engage with when the said hook releases the fall-block.

In testimony whereof I affix my signature in presence of two witnesses.

SIGURD EDLING.
